(57) **CLAIM**

I claim the ornamental design for the submersible LED light, as shown and described.

DESCRIPTION

FIG. 1 is a first perspective view of a submersible LED light of my new design;

FIG. 2 is a second perspective view of the submersible LED light of FIG. 1, viewed from another aspect;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 shows the submersible LED light of FIG. 1 in a first state of use;

FIG. 10 shows the submersible LED light of FIG. 1 in a second state of use;

FIG. 11 shows the submersible LED light of FIG. 1 in a third state of use;

FIG. 12 shows the submersible LED light of FIG. 1 in a fourth state of use;

FIG. 13 shows the submersible LED light of FIG. 1 in a fifth state of use;

FIG. 14 shows the submersible LED light of FIG. 1 in a sixth state of use; and,

FIG. 15 shows the submersible LED light of FIG. 1 in a seventh state of use.

The broken lines showing of the environment are for illustrative purposes only and form no part of the claimed design.

1 Claim, 15 Drawing Sheets
